UNITED STATES PATENT OFFICE

CHARLES RICHTER, OF NEW YORK, N. Y., ASSIGNOR TO CHATTAM METAL SPINNING AND STAMPING CORPORATION, OF NEW YORK, N. Y.

DESIGN FOR A LIGHTING FIXTURE

Application filed August 31, 1929. Serial No. 32,638. Term of patent 3½ years.

To all whom it may concern:

Be it known that CHARLES RICHTER, citizen of the United States, residing at New York, in the county of New York and State of New York, has invented a certain new, original, and ornamental Design for a Lighting Fixture, of which the following is a specification, reference being had to the accompanying drawing, forming part thereof.

The figure is a perspective view of a lighting fixture showing my design.

I claim—

The ornamental design for a lighting fixture, as shown.

In testimony whereof I affix my signature.

CHARLES RICHTER.
